The ornamental design for an electrical cord connection cover, as shown and described.

DESCRIPTION

FIG. 1 is a top perspective view for an electrical cord connection cover showing our new design in an open position.

FIG. 2 is a top plan view thereof;

FIG. 3 is bottom plan view thereof;

FIG. 4 is a right side elevational view thereof;

FIG. 5 is a left side elevational view thereof;

FIG. 6 is a rear elevational view thereof;

FIG. 7 is a front elevational view thereof; and,

FIG. 8 is a top perspective view thereof, wherein the electrical cord connection cover is in a closed position.

The stippled surface represents a contrasting surface texture.
